UNITED STATES PATENT OFFICE.

WILLIAM A. WILLIAMS, OF BARTON, OHIO.

TIRE-VALVE-UNSEATING DEVICE.

1,225,910.

Specification of Letters Patent. Patented May 15, 1917.

Application filed November 7, 1916. Serial No. 129,939.

To all whom it may concern:

Be it known that I, WILLIAM A. WILLIAMS, a citizen of the United States of America, and resident of Barton, county of Belmont, and State of Ohio, have invented 5 certain new and useful Improvements in Tire-Valve-Unseating Devices, of which the following is a specification.

This invention relates broadly to valve- 10 unseating devices, and more particularly to a device for maintaining a tire-valve in unseated, or air-releasing position.

The primary object of the invention is to provide a device whereby the valve of a 15 pneumatic tire may be depressed to and maintained in unseated position, as for releasing the air from the tire.

A further object is to provide a tool de- 20 signed for ready application to a valve-tube and which involves a spring structure adapt- ed for assuming clamping engagement with said valve-tube in a position in which a valve-depressing member is held in valve- unseating position.

25 A still further object is to provide a de- vice of the character mentioned which may be applied instantly by slipping the clamp longitudinally over the valve-tube and in which the valve-depressing member is so lo- 30 cated that it is guided or directed into valve- unseating engagement with the outwardly extending end of the valve-stem by the mere act of applying said clamp, or without the exercise of care or attention on the part of 35 the user.

With these and other objects in view, the invention resides in the features of construction which will hereinafter be exemplified, reference being had to the accompanying 40 drawings, in which—

Figure 1 is a perspective view of the invention;

Fig. 2 is an enlarged side elevation of the same, illustrating its application; and

45 Fig. 3 is a similar elevation viewed from a point at a right angle to the view point in Fig. 2.

In said drawings like designating char- acters distinguish like parts throughout the 50 several views.

The invention is composed of a single length of wire, one end-portion of which is

bent to form two substantially parallel members 1 and 2 which are joined at one end by a spring coil 3, said member 1 con- 55 sisting of a long terminal finger adapted to yieldingly engage a side of the body-portion of a valve-tube A and constituting a part of a clamp whereby such tube may be ad- justably embraced. The portion of said 60 clamp opposed to and coöperating with said finger 1 is constituted by a loop of approxi- mately rectangular form and consisting of two horizontally disposed substantially 65 semi-circular members 5 and 6, the lower of 70 which is adapted to conformably embrace the body-portion 4 of said valve-tube while the upper member 6 thereof is adapted to conformably embrace the usual reduced end-portion 7 of said tube. Further, said upper 75 member 6 of said loop is so located that it will seat upon the shoulder 8 intermediate the portions 4 and 7 of said tube for pre- venting advancement of the clamp over the tube beyond the point at which the valve is adequately unseated, as will subsequently be explained.

Said rectangular tube-embracing loop of the clamp has its free end composed of a substantially vertical member 9 intermediate 80 and uniting the corresponding ends of the semi-circular members 5 and 6, while its op- posite end is composed of the lower portion of a vertical member 10 which rises from the corresponding end of the member 5 and 85 10 which is closely embraced at a point ap- proximately midway between its ends by a coil 11 formed in the wire at the corre- sponding end of the member 6 of said loop. The continuation of the wire beyond said 90 coil 10 is the member 2 hereinbefore mentioned.

A terminal member 12 is provided by forming a return bend 13 in the wire at the upper, or outer, end of the vertical member 95 10, said member 12 being so spaced away from said member 10 and so located with respect to the other parts of the device that it will enter the end of the valve-tube A in accurate axial alinement with the latter 100 when the clamp constituted by the rectangular loop and spring finger 1 is slipped over said tube. Thus, when applied, the terminal member 12 accurately engages the out-

wardly projecting end of the stem 14 of the valve to be unseated, said stem being normally disposed in a central or axial position within said tube. To insure against 5 said member 12 missing the end of said stem when introduced, as when the latter occupies a slightly inclined position, as sometimes happens due to the valve occupying an improperly or imperfectly seating position, the inner end of said member is preferably flattened or upset slightly to form a head 15 approximating in shape that commonly employed on small nails or brads. The length of said member 12 is preferably 10 so proportioned relatively, or has its end so located with respect to the position of the loop member 6, that, when the clamp occupies seated position with said member 6 resting upon the shoulder 8 of the valve-tube, it will have depressed the valve stem 14 to an extent which effectually unseats the valve. 20

As is apparent, application of the device 25 to valve-unseating position upon the valve-tube is the work of an instant. Further, while the clamp is self-retaining the spring finger 1 forming a part thereof is sufficiently resilient to permit of application and removal without injury to the threads of the 30 valve-tube.

What is claimed is—

1. A tire-valve-unseating device consisting of a single-wire bent to form a resilient 35 clamp embodying a spring coil, said clamp being adapted for slipping over a valve-tube and having a member designed to engage and seat upon the valve-stem for depressing the latter.

2. A tire-valve-unseating device composed 40 of a single length of wire shaped to form opposed resilient members adapted for assuming clamping engagement with a valve-tube, a spring coil intermediate said members, and a member adapted for entrance within the end of said tube for engaging and depressing the valve-stem.

3. A tire-valve-unseating device composed 45 wholly of a single length of wire and embodying opposed resilient members adapted to be slipped longitudinally over the end of a valve-tube and to assume clamping engagement with the latter, and a member formed of one of the wire terminals carried in fixed relation to said members and adapted to enter said tube in axially aligned relation thereto for engaging and depressing the valve-stem.

4. A tire-valve-unseating device composed 50 wholly of a single length of wire and adapted to seat upon a valve-tube in clamping relation to the body portion of the latter, said device comprising a pair of clamp-members designed to be slipped longitudinally into gripping engagement with said tube, one of said members embodying means for

limiting the extent to which the members may be applied, and a member adapted to automatically assume valve-unseating relation to the valve-stem as said members are applied to said tube. 70

5. A tire-valve-unseating device adapted 75 to seat upon a valve-tube in clamping relation to the latter, said device being composed wholly of a single length of wire bent to form opposing clamp-members of which one embodies a stop adapted to seat against the shoulder located intermediate the body of the valve-tube and the reduced end of the latter, and a terminal member adapted to automatically seat upon and depress the valve-stem as the clamp-members are moved to seated position. 80

6. A tire-valve-unseating device adapted 85 to seat upon a valve-tube in clamping relation to the latter, said device comprising a single length of wire bent to form opposing clamp-members, a spring coil formed intermediate said members, and a terminal member so located with respect to said clamp-members that the act of applying the latter serves to carry said terminal member into valve-unseating relation to the valve-stem. 90

7. A tire-valve-unseating device adapted 95 to seat upon a valve-tube in clamping relation to the latter, said device comprising a single length of wire bent to form opposing clamp-members and an intermediate spring coil, the opposite wire terminal being shaped to constitute a member which automatically depresses the valve-stem as said clamp-members are applied in seating position. 100

8. A tire-valve-unseating device adapted 105 to seat upon a valve-tube in clamping relation to the latter, said device comprising a single length of wire shaped to form a resilient finger at one of its terminals and a valve-stem-engaging member at its opposite terminal, an intermediate portion of the wire being shaped to form a valve-tube-engaging member disposed in opposed relation to said finger. 110

9. A tire-valve-unseating device adapted 115 to seat upon a valve-tube in clamping relation to the latter, said device comprising a single length of wire shaped to form a finger at one of its terminals and a valve-stem-engaging member at its opposite terminal, and an intermediate portion adapted to partially embrace the valve-tube and disposed in opposing relation to said finger. 120

10. A tire-valve-unseating device adapted 125 to seat upon a valve-tube in clamping relation to the latter, said device comprising a single length of wire shaped to form a finger at one of its terminals and a valve-stem-engaging member at its opposite terminal, an intermediate portion adapted to partially embrace the valve-tube and disposed in op- 130

posing relation to said finger, and a spring coil formed in the wire intermediate the last-mentioned portion and said finger whereby the latter is rendered resilient with
5 respect to said portion for yieldingly gripping the valve-tube.

In testimony whereof, I affix my signature in presence of two subscribing witnesses.

WILLIAM A. WILLIAMS.
